UNITED STATES PATENT OFFICE.

KATHERINE B. FULD, OF BALTIMORE, MARYLAND.

TOY.

1,333,613.

Specification of Letters Patent. Patented Mar. 16, 1920.

Application filed August 21, 1919. Serial No. 318,856.

To all whom it may concern:

Be it known that I, KATHERINE B. FULD, a citizen of the United States, residing at Baltimore, State of Maryland, have invented 5 certain new and useful Improvements in Toys, of which the following is a specification.

This invention relates to toys and more particularly to that class of such devices known in the art as figure toys, and has for its object the provision of an amusing and economical toy adapted to represent a comical subject, such as a mule and its rider, mechanism being provided whereby to produce a series of positions of the device to effectively imitate the varied antics thereof.

With the foregoing and other objects in view as will from time to time hereinafter appear this invention consists in the peculiar 20 combination and operation of the related parts of a toy as described in the annexed specification and more particularly pointed out in the appended claims.

Referring to the accompanying drawing 25 illustrating an embodiment of the invention and in which like characters of reference indicate like parts wherever used, dotted lines being employed to indicate certain changes of position assumed by the device,

30 Figure 1 is a side elevation partly broken away for the sake of illustration;

Fig. 2 is a side elevation showing some of the various positions assumed by the device, and

35 Fig. 3 is a detail section taken through the head of the animal, the representation of the reins and the hand of the rider.

40 4 designates a platform provided with suitable devices 5 adapted to assist in the propulsion thereof, and a central slot 6. The platform 4 is carried by a bracket 7, supporting a pair of wheels 8 by means of an axle 9, which is bent to form a crank arm 10 carrying by means of an eye 11 a 45 U-shaped member 12 terminating in arms 13, which carry a rod 14 pivotally supporting the rear legs 15 of a fanciful figure adapted to represent the profile of a mule or other animal having a sharply inclined 50 upper or back representing portion, having a tail portion 15 and fore legs 17 which are pivotally carried at 18 between blocks 19 mounted upon the platform 4.

55 Suitably positioned on the back of the figure, in order to present the appearance of being mounted thereon, is a fanciful fig-

ure 20 designed to represent a man or the like and having a projecting portion 21 representing the hands thereof through which passes a wire member 22 representing reins, 60 and also passing through the head 23 of the mule figure and pivotally secured thereto at 24. Leg members 25 are eccentrically pivoted on either side of the figure 20 at 26 and are provided with an enlargement 27 65 adapted to cause a rocking movement thereof.

The figure 20 has the front of its body portion rounded so as to cause it to travel up and down the inclined back portion of 70 the animal in the movements of the latter, thus producing in its extreme forward movement the effect of being thrown over the head of the animal, as indicated in dotted lines in Fig. 2.

75 The mechanism just described functions as follows during operation:

The device is caused to move in either a forward or a rearward direction, imparting by means of the wheel 8 a rotary movement 80 to the axle 9, causing a reciprocating movement of the U member 12 carried by the crank arm 10, such movement causing the figure of the mule to rock about its fore leg pivot 18 to assume a number of positions imitating the bucking thereof. The figure 20 being free to move along the back of the mule figure and pivotally secured to the wire 22 will assume the various positions of a rider of such an animal, somewhat exaggerated in order to provide an amusing device, the legs 25 being free to move about the pivot 26 and being over-balanced by the enlargement 27 will assume various positions during the reciprocation and operation 90 95 of the device.

I realize that considerable variation is possible in the details of construction and arrangement of parts without departing from the spirit of my invention, and I 100 therefore do not intend to limit myself to the specific form shown and described.

I claim:

1. In a toy, in combination, a wheel supported platform, a figure having legs of unequal length, the longer leg thereof being pivotally connected to said platform, means connecting the shorter leg of said figure with the wheel carrying axle to cause the figure to rock on its pivot connection with the platform as said axle revolves, and a second figure pivotally mounted on said first named 110

figure and adapted to be moved by the same in the rocking movements thereof.

2. In a toy, in combination, a wheel supported platform, a figure having legs of unequal length, the longer leg thereof being pivotally connected to said platform, means connecting the shorter leg of said figure with the wheel carrying axle to cause the figure to rock on its pivot connection with the platform as said axle revolves, and a second figure having enlarged leg members eccentrically pivoted thereon, said second figure being pivotally mounted on said first named

figure whereby said last named figure will be bodily moved by the rocking movements 15 of said first named figure and its enlarged leg members be caused to swing on their pivotal connection with the figure to which they are attached.

In testimony whereof I affix my signature 20 in presence of two witnesses.

KATHERINE B. FULD
